UNITED STATES PATENT OFFICE.

EDWARD CONLEY, OF CINCINNATI, OHIO.

IMPROVEMENT IN RAILROAD-STATION INDICATORS.

Specification forming part of Letters Patent No. **101,437**, dated April 5, 1870.

To all whom it may concern:

Be it known that I, EDWARD CONLEY, of Cincinnati, in the county of Hamilton and State of Ohio, have invented a new and Improved Railroad-Station Indicator; and I do hereby declare that the following is a full, clear, and exact description thereof, which will enable others skilled in the art to make and use the same, reference being had to the accompanying drawings, forming part of this specification.

The object of my invention is improvement in railroad-indicators; and the invention consists in the particular arrangement of parts, as hereinafter specified.

Figure 1 is a perspective view of my improved apparatus with the end of the case removed and the cover raised. Fig. 2 is a perspective view of the rollers and the belt.

Similar letters of reference indicate corresponding parts.

A is a small case, adapted to be set up in any convenient position in a car, in which is placed a small frame, B C, supporting the operating-roller D, guide-rollers E, E', and E'', and tension-rollers F and G.

I is an endless belt arranged on the guide-rollers, and the operating-roller to be moved back and forth when the roller D is turned. Two of the guide-rollers E are placed near the bottom of the frame as may be, and the other two are placed as close as can well be under the operating-roller D, which is at the top of the said frame, so that the belt may be caused to traverse back and forth as much as possible, in order to get as long a belt as possible within the smallest space. The guide-rollers E and E'' are arranged so that when in position in the case A they will stand, respectively, above and below the opening K, through which to see the names on the canvas and cause it to move past the said opening. The roller E'' is made adjustable up and down in the frame B C, and the tension-rollers F G are made adjustable relatively to the roller D, so as to increase or diminish the friction thereon, as may be required, to cause the belt to work properly. The adjustable tension-roller G is also used, in connection with the adjustable

guide-roller E and the fixed guide-roller E', for adjusting the belt and the names thereon relatively to the opening K. The said names are spaced on the canvas the same distance apart as the surface movement of the operating-roller D at one stage; but, owing to the variations in the tension of the belt and other causes, the belt will, from time to time, get out of its proper position on the rollers relatively to the opening, so that the names will stop too high or too low. If too low, the roller E'' is raised and the roller G forced down, and, if too high, the said rollers are moved in the opposite direction.

The roller D is provided with a ratchet-wheel, M, a pawl-arm, N, and double-acting pawl O, the latter being pivoted to the pawl-arm and arranged for working the ratchet-wheel either way. The free end of the pawl-arm is connected to the slide Q, which is intended to be worked back and forth by the conductor or other person, or in one direction by him and the other way by a spring, weight, or other equivalent device. The operating-roller is in this way turned in either direction, as is required by the running of the cars back and forth on the roads.

The aforesaid improved apparatus is applicable for use on street-cars, steamboats, and all other conveyances as well; and a bell may be attached to the slide-bar, to be struck or caused to be struck by it, to attract the attention of passengers to it.

I do not confine myself to the number of rollers herein shown, but propose to use any preferred number, according to the length of the canvas.

Having thus described my invention, I claim as new and desire to secure by Letters Patent—

The combination of case A, having opening K, frame B C, roller D, guide-rollers E E' E'', tension-rollers F G, endless belt I, ratchet M, arm N, pawl O, and slide Q, all constructed and arranged as and for the purpose specified.

EDW. CONLEY.
